UNITED STATES PATENT OFFICE.

HEINRICH KOEHLER, OF BOCHUM, PRUSSIA, GERMANY, ASSIGNOR TO DIE GESELLSCHAFT FÜR STAHLINDUSTRIE, OF SAME PLACE.

ROLLING-MILL FOR TRAMWAY-RAILS.

SPECIFICATION forming part of Letters Patent No. 311,250, dated January 27, 1885.

Application filed May 1, 1884. (No model.) Patented in Belgium April 19, 1884, No. 64,876; in France April 19, 1884, No. 161,627; in England April 19, 1884, No. 6,577; in Luxemburg April 19, 1884, No. 383; in Germany April 20, 1884, No. 29,977; in Spain September 1, 1884, No. 4,155, and in Austria-Hungary September 21, 1884, No. 14,936 and No. 42,311.

To all whom it may concern:

Be it known that I, HEINRICH KOEHLER, a subject of the King of Prussia, residing at Bochum, Prussia, German Empire, have invented certain new and useful Improvements 5 in Rolling-Mills for Tramway-Rails; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 My invention relates to improvements in the construction and arrangement of that class of rolling-mills employed for grooving or channeling the head of railway-rails.

20 The invention consists, essentially, in the combination, with the channeling-roll, of a cylindrical supporting-roll for the rail, both driven positively, and of guide-rolls applied to opposite sides of the web and foot of the rail between the channeling and supporting rolls.

25 In the accompanying drawings, Figure 1 shows by a vertical transverse section through the roll-bearings a rolling-mill embodying my improvements, and Fig. 2 is an elevation thereof.

30 Like letters of reference indicate like parts in the above figures of drawings.

35 In some of the rolling-mills of the class to which this invention relates, as heretofore constructed, the channeling of the rail-head is effected by a flanged roll projecting into the groove or caliber of the finishing-roll, the channeling-roll being rotated by friction. This gives rise to a speedy wear of the channeling-roll from undue friction, also owing to the necessarily small diameter such a roll must have 40 in order to perform its function properly. In other constructions a vertical driving-roll is employed for channeling the rail-head, and with this roll are combined two horizontal guide-rolls of the caliber of the finishing-rolls, said guide-rolls being usually mounted at the end of the rolls of an ordinary mill-frame. In this case the foot of the rail is supported from flanges formed on the guide-rolls, which ar-

range ment also gives rise to a great amount of 50 friction, while the strain or resistance to the pressure necessary to channel the rail-head is supported on an axial line by the roll-bearings, which is undesirable.

To avoid these difficulties I employ an upper driven channeling-roll, a lower driven cylindrical supporting-roll, and two finishing-rolls encompassing the web of the rail to prevent its being crushed during the process of channeling, said rolls being rotated by friction. 60 These rolls in themselves constitute a channeling and finishing mill wherein the roughened-down rails are channeled and finished.

A and C C indicate the four rolls which constitute my improved channeling and finishing mill. In the accompanying drawings I have shown the channeling-roll B mounted above the supporting-roll A, and the guide and finishing rolls C on opposite sides thereof. Although I prefer this arrangement, yet it is 70 obvious that the relative positions of the rolls A, B may be reversed, and also that the position of the rolls A, B relatively to that of the rolls C may also be reversed, without in any manner changing their function.

75 The rolls A, B are mounted, as usual, in boxes E, adjustable by means of set-screws K in the cheeks of the double standard G. The rolls C, on the contrary, are mounted in boxes or frames F, secured to the standard by means 80 of four or more bolts, f. The trunnions a' b' of the rolls A, B are provided with the usual couplings, and are to be driven in opposite directions.

As shown, the roll A supports the foot of the 85 rail R, the roll B, provided with the channeling-flange, channels and finishes the rail-head, while the rolls C, encompassing the web of the rail R and projecting between the rolls A, B, serve to properly guide the rail on its passage 90 through rolls A, B, support the web of the rail R, to prevent its being crushed, and finish said web.

95 Wedge-blocks I between the bearings E and F, together with the set-screws K, serve to adjust the rolls relatively to one another and the rail, and, as above set forth, the rolls C are driven by friction.

Having now described my invention, what I claim, and desire to secure by Letters Patent of the United States, is—

The combination, in a rolling-mill for channeling the head of railway-rails, of a channeling-roll, a cylindrical roll for supporting the rail, both driven positively, and two web-rolls for supporting the web of the rail against crush-

ing, said rolls constituting a finishing rolling-mill, as described, for the purpose specified. 10

In testimony whereof I affix my signature in presence of two witnesses.

HEINRICH KOEHLER.
